UNITED STATES PATENT OFFICE.

EDMOND KENNY, OF NEW BRIGHTON, NEW YORK, ASSIGNOR TO MERCANTILE CORPORATION, OF NEW YORK, N. Y., A CORPORATION OF NEW YORK.

ROTARY CUTTER-HEAD.

1,087,953.

Specification of Letters Patent. Patented Feb. 24, 1914.

Application filed September 21, 1912, Serial No. 721,529. Renewed August 20, 1913. Serial No. 785,816.

To all whom it may concern:

Be it known that I, EDMOND KENNY, a citizen of the United States, and a resident of New Brighton, in the county of Richmond 5 and State of New York, have invented certain new and useful Improvements in Rotary Cutter-Heads, of which the following is a specification.

This invention relates to rotary cutter heads and has for its object to provide a device of the class specified having members of simple construction and which can be removably mounted whereby they can be readily sharpened or replaced.

15 My improvements are illustrated in their preferred form in the accompanying drawings wherein—

Figure 1 is a perspective view of my improved cutter head, assembled ready for use. 20 Fig. 2 is a side elevation of the body portion thereof and Fig. 3 is an end elevation corresponding therewith. Fig. 4 is a plan view of one pair of cutting members showing their relative positions when assembled on the body portion and Fig. 5 is a side elevation thereof. Fig. 6 is a plan view of another cutter member and Figs. 7 and 8 are side and end views respectively thereof. Fig. 9 is a 25 plan view of another pair of cutting members and Fig. 10 is a side elevation thereof. Fig. 11 is a plan view of a series of blanks as cut from a continuous web with my improved device.

My improved cutter head pertains to that 30 well known class of rotary cutters which are mounted upon a fixed axis for rotative coaction with a cylindrical cutting bed.

Body portion 2 is preferably provided 35 with a cylindrical hole 3 axially thereof through for mounting on a convenient arbor or spindle. The ends of said body portion 40 may be slotted as at 4 and said slotted ends may be clamped to the usual carrying arbor or shaft by means of clamps as 5. Said body 45 portion is provided with a plurality of plain faces as 6, 7, 8 to which cutting members as 17, 18 are secured by some suitable means such as screws 12. Said cutting members 50 may be located on their respective cutter 55 head faces by the usual dowels as 13. Said plain faces are preferably parallel with the axis of the cutter head and may comprise faces of a plurality of prisms as 14, 15, 16, the axes of said prisms coinciding with the 60 axis of the cutter head. The particular form

of cutting head which I have chosen to illustrate is adapted for cutting successive diamond shaped envelop blanks 20 from a continuous web 21 and that character of cutting requires as a major part thereof a 60 skewed or slanting cut 22 widthwise the continuous web. I therefore arrange said prisms skewed relatively to each other, Figs. 1, 2 and 3, whereby cutting members as 17, 18, 19 mounted on consecutive faces of 65 prisms 14, 15, 16 respectively are arranged in a continuous substantially helically disposed line of cutting edge.

On face 7 of middle prism 15 opposite cutter 18 I arrange cutter 10 which in coaction with cutter 18 cuts out the waste portion or chip 23 between consecutive blanks; and on faces 6 and 8 of prisms 14, 16 respectively I locate cutters 9 and 29 for coaction with cutters 17 and 19 respectively for 70 cutting out the V waste portions 24. Diametrically opposite faces 6, 7, 8 respectively, I mount other cutters similar to those upon said faces 6, 7, 8, whereby at each revolution of my improved cutter head two lines of 75 cut 22 are produced. For cutting out V portions 25, 25 I mount on face 26 of prism 14 and face 28 of prism 8, V cutters as 11, and upon those opposite faces 36, 38 respectively, of prisms 14, 16 I mount duplicates of said 80 cutters 11 for cutting alternate V notches 27, 27. All the cutting edges of cutters as 10, 11, 17, 18 are equidistant from the axis of 85 the cutter head so that said cutter head may coact with a plane surface on which the web 90 is laid or with a coacting rotary cylindrical member as well known in the art. As illustrated herein, said prisms 14, 15, 16 are quadrilateral and prisms 15, 16 are preferably rectangular.

95 While I have chosen to illustrate my improved cutter head as composed of quadrilateral prisms it is obvious that if I desire to make three cuts at each revolution of the cutter head, that result may be accomplished 100 by providing said prisms with six faces each, whereby an additional set of cutters may be mounted on said cutter head. Or by providing said cutter head body with prisms having eight sides each, four complete sets 105 of cuts may be made at each revolution. It will also be obvious to those skilled in the art that said cutter head might be provided with one set of cutters only, whereby at each revolution only one complete set of cuts will 110

be made. I prefer, however, to use the arrangement illustrated as being the most practicable and serviceable in use.

I claim:

5. 1. A rotary cutter head including in combination, a body portion having a plurality of plain faces parallel with the axis of the cutter head and skewed relatively to each other, cutting members fixed to two or more of said faces, the cutting edges thereof comprising a continuous substantially helically disposed line of cutting edge. 70
10. 2. A rotary cutter head including in combination, a body portion comprising a plurality of prisms each of whose axes coincide with the axis of rotation of said cutter head, said prisms being skewed relatively to each other and cutting members fixed to one or more of the faces of each prism of said body portion, the cutting edges of said cutters being at all points equidistant from the axis of the cutter head. 75
15. 3. A rotary cutter head including in combination, a body portion comprising a plurality of prisms each of whose axes coincide with the axis of rotation of said cutter head, said prisms being skewed relatively to each other and cutting members fixed to one or more of the faces of each prism of said body portion, the cutter bearing faces of said prisms being equidistant from the axis of revolution and the cutting edges of said cutters being at all points equidistant from the axis of the cutter head. 80
20. 4. A rotary cutter head including in combination, a body portion comprising a plurality of prisms each of whose axes coincide with the axis of rotation of said cutter head, said prisms being skewed relatively to each other and cutting members fixed to one or more of the faces of each prism of said body portion, the cutting edges of said cutting members being at all points equidistant from the axis of the cutter head. 85
25. 5. A rotary cutter head including in combination, a body portion comprising a plurality of prisms each of whose axes coincide with the axis of the cutter head, said prisms being skewed relatively to each other, cutting members fixed to one or more of the faces of each prism of said body portion, the cutting edges of said cutting members comprising one or more continuous substantially helically disposed lines of cutting edge 90
30. traversing contiguous faces of said prisms respectively. 95
35. 6. A rotary cutter head including in combination, a body portion comprising a plurality of prisms each of whose axes coincide with the axis of rotation of said cutter head, said prisms being skewed relatively to each other and cutting members fixed to two or more of the faces of each prism of said body portion, the cutting edges of said cutters being at all points equidistant from the axis of the cutter head. 100
40. 7. A rotary cutter head including in combination, a body portion comprising a plurality of quadrilateral prisms each of whose axes coincide with the axis of rotation of said cutter head, said prisms being skewed relatively to each other and cutting members fixed to two or more of the faces of each prism of said body portion, the cutting edges of said cutters being at all points equidistant from the axis of the cutter head. 105
45. 8. A rotary cutter head including in combination, a body portion comprising a plurality of quadrilateral prisms each of whose axes coincide with the axis of rotation of said cutter head, said prisms being skewed relatively to each other and cutting members fixed to two or more of the faces of each prism of said body portion, the cutting edges of said cutters being at all points equidistant from the axis of the cutter head. 110
50. 9. A rotary cutter head including in combination, a body portion comprising three prisms each of whose axes coincide with the axis of rotation of said cutter head, said end prisms being skewed relatively to the central prism and cutting members fixed to two or more of the faces of each prism of said body portion, the cutting edges of said cutters being at all points equidistant from the axis of the cutter head. 115
55. 10. A rotary cutter head including in combination, a body portion comprising a central rectangular prism, a diamond prism adjacent to one end thereof and a rectangular prism adjacent to the other end thereof, the axes respectively of said prisms coinciding with the axis of revolution of the cutter head, said end prisms being skewed relatively to each other and to the central prism and cutting members fixed to one pair of opposite faces of said central prism and cutting members fixed to both pairs of opposite faces of the end prisms. 120
60. 11. A rotary cutter head including in combination, a body portion comprising a central rectangular prism, a diamond prism adjacent to one end thereof and a rectangular prism adjacent to the other end thereof, the axes respectively of said prisms coinciding with the axis of revolution of the cutter head, said end prisms being skewed relatively to each other and to the central prism and cutting members fixed to one pair of opposite faces of said central prism and cutting members fixed to both pairs of opposite faces of the end prisms, the cutting edges of said cutters being at all points equidistant from the axis of the cutter head. 125
65. 12. A rotary cutter head including in combination, a body portion comprising a central rectangular prism, a diamond prism adjacent to one end thereof and a rectangular prism adjacent to the other end thereof, the axes respectively of said prisms coinciding with the axis of revolution of the cutter head, said end prisms being skewed relatively to each other and to the central prism and cutting members fixed to one pair of opposite faces of said central prism and cutting members fixed to both pairs of opposite faces of the end prisms, the cutting edges of said cutters being at all points equidistant from the axis of the cutter head. 130

12. A rotary cutter head including in combination, a body portion comprising a central rectangular prism, a diamond prism adjacent to one end thereof and a rectangular prism adjacent to the other end thereof, the axes respectively of said prisms coinciding with the axis of revolution of the cutter head, said end prisms being skewed relatively to each other and to the central prism and cutting members fixed to one pair of opposite faces of said central prism and cutting members fixed to both pairs of opposite faces of the end prisms, the cutting edges of said cutters being at all points equidistant from the axis of the cutter head and those cutting members on opposite faces of each prism having substantially the same cutting profile.
13. A rotary cutter head including in combination a body portion having a plurality of plain faces, cutting members fixed to two or more of said faces, the cutting edges thereof comprising a continuous substantially helically disposed line of cutting edge.
14. A rotary cutter head including in combination, a body portion comprising a plurality of prisms and cutting members fixed to one or more of the faces of each prism of

said body portion, the cutting edges of said cutters being at all points equidistant from the axis of the cutter head.

15. A rotary cutter head including in combination, a body portion comprising a plurality of prisms and cutting members fixed to one or more of the faces of each prism of said body portion, the cutter bearing faces of said prisms being equidistant from the axis of the cutter head.

16. A rotary cutter head including in combination a body portion comprising a plurality of prisms each of whose axes coincide with the axis of the cutter head, cutting members fixed to one or more of the faces of each prism of said body portion, the cutting edges of said cutting members comprising one or more continuous substantially helically disposed lines of cutting edge traversing contiguous faces of said prisms respectively.

Signed at Dayton, in the county of Montgomery and State of Ohio this 7th day of Sept. 1912, before two subscribing witnesses.

EDMOND KENNY.
